VIBRATORY REED MUSICAL INSTRUMENT

Benjamin F. Miessner, Harding Township, Morris County, N. J., assignor to Miessner Inventions Inc., Harding Township, Morris County, N. J., a corporation of New Jersey

Application November 21, 1949, Serial No. 128,580

3 Claims. (Cl. 84—376)

1

This invention relates to air-vibrated, reed type musical instruments, such as accordions and the like, and more particularly to a novel arrangement of air passageways and associated valves rendering unidirectional the flow of air past the reeds upon compression and expansion of the bellows, whereby the total number of reeds is reduced to one half that required in similar instruments of conventional design.

Ordinarily an accordion has two keyboards disposed on opposite sides of the bellows, one of conventional organ type which serves generally for the solo or melody parts of the music and the other of the push button type which serves for the accompanying parts consisting of musical chords of various types and frequencies. Conventional accordions require two complete sets of vibratory reeds, that is, two individual reeds are required for each tone to be reproduced. One reed is effective to produce the tone when the bellows are compressed and the other reed is effective to produce an identical tone when the bellows are expanded. The reason for the dual reed complement is due to the fact that a free reed (one which vibrates clear of the air passageway) cannot be set into sustained vibrations when the air current causes an initial flexing of the reed in a direction away from the air aperture in the reed block.

In my copending U. S. application Serial No. 117,992, filed September 27, 1949, now abandoned, I disclose one method of overcoming the requirement for a dual set of reeds by providing a single set of reeds of novel construction whereby each reed is capable of vibration with the passage of air in either direction. The present invention concerns itself with a different solution to the problem, namely, by the provision of a structure and valve system which maintains a unidirectional flow of air through a single set of conventional, single reeds for both compression and expansion of the accordion bellows.

An object of this invention is the conservation of weight, space and cost in an accordion or the like by the provision of an air system requiring only a single reed to produce a given tone under compression and expansion of the accordion bellows.

An object of this invention is the provision of a novel air passageway and valve arrangement for accordions and the like wherein a single reed is subjected to a unidirectional flow of air during compression and expansion of the bellows.

An object of this invention is the provision of an air control system for accordions and the like

2

comprising a pair of air chambers, a vibratory reed mounted over an opening between the air chambers, an airport between each air chamber and the atmosphere, an airport between each air chamber and the air reservoir formed by the instrument bellows, and one way air valves associated with each port and so arranged that a transfer of air between the air reservoir and the atmosphere upon compression or expansion of the bellows results in a unidirectional flow of air through the opening between the air chambers.

These and other objects and advantages will become apparent from the following detailed description when taken with the accompanying drawings. It will be understood the drawings are for purposes of illustration and are not intended to define the scope or limits of the invention, reference being had for the latter purpose to the appended claims.

20 In the drawings wherein like reference characters denote like parts in the several views:

Figure 1 is an isometric view of a conventional pair of reeds mounted on a single reed block and as now required to produce a single tone upon compression and expansion of the bellows of an accordion;

Figure 2 is a similar view of a single reed which may be used in conjunction with my invention;

Figure 3 is a central cross sectional view illustrating my novel arrangement of the air chambers, airports and associated one way valves when the accordion bellows are being expanded; and

Figure 4 is a fragmentary view similar to that of Figure 3 and illustrating the position of the valves when the bellows are being compressed.

Figure 1 illustrates a dual reed as presently required to produce a given tone upon compression and expansion of the bellows of an accordion. The reeds 10, 10' are mounted individually on opposite sides of a reed block 11 as by the rivets 12, 12', respectively, each reed being aligned with an associated aperture or air passageway 13, 13'. As is well-known, the distal end and the marginal edges of the reed are spaced from the walls defining the associated aperture whereby the reed is free to vibrate within the aperture without touching the reed block. Also, the reed is inclined somewhat so that the distal end of the reed is spaced from the face of the reed block.

In an accordion, or the like, the reed block 11 is mounted in an air chamber whereby changes in air pressure brought about by the compression or expansion of the bellows results in a passage of air through the apertures 13, 13'. Assume now that compression of the bellows causes a flow of

air through the apertures 13, 13' in the direction indicated by the arrows *a*, *a*. The mass of air rushing through the relatively open aperture 13 and pass the edges of the reed 10 produces vortexes which draw the reed toward the aperture. When the reed 10 is drawn into the aperture 13 the latter effectively is closed whereupon the flow of air therethrough is reduced substantially. Consequently, the resilient reed tends to return to its initial position which effectively reopens the aperture and the cycle is repeated. The net result is a sustained vibration of the reed. On the other hand, the reed 10' initially flexes away from its associated aperture thereby effectively opening up the aperture to an extent whereby a balance is established between the air pressure exerted upon the face of the reed and the compliance characteristics of the particular material of which the reed is made. Thus, the reed 10' does not vibrate.

Upon extension of the accordion bellows a reverse action takes place, that is, air current flows in the direction of the arrows *b*, *b*. Under this condition the reed 10' vibrates to produce the tone while the reed 10 is ineffective. With both reeds adjusted to vibrate at the same frequency identical tones are produced upon compression and expansion of the bellows.

In the practice of my invention only a single reed is required to produce a given tone when the bellows are either compressed or expanded. Such a unit is shown in Figure 2, wherein the vibratory reed 15 is mounted on a reed block 16, the latter being provided with holes 17 whereby the unit may be mounted upon a reed board or other surface.

Reference is now made to Figures 3 and 4 which show the features of my novel chamber and valve system for obtaining a unidirectional flow of air past the vibratory reed when the bellows are either compressed or expanded. The illustrations are in schematic form to afford a clear understanding of the structure as it would be difficult to illustrate an actual structural arrangement as applied in an actual accordion. The drawings, therefore, do not represent actual physical structure except in its operational symbolism. There is shown in the drawings the two halves of an accordion connected by a bellows of conventional type. Since the action of both halves is the same, only one is shown in detail, and that one only to the extent necessary for a proper understanding of the invention.

The bellows 22 are secured to the opposed end plates 21 and 22 as by metallic strips 23 that are fastened to the plates by means of the screws 24 and nuts 25. A housing 26 is secured to the upper plate 21 as by the screws 27 and nuts 28, a resilient gasket 29 serving to make the joint air tight. The housing 26 is divided into two air chambers A and B by the plate 20 secured in place by the screws 31 and cooperating nuts 32. An air passageway between the atmosphere and the air chamber B is formed by the tube 35 that may be secured to the plate 21 and the plate 30 by cement, or etc. A similar air passageway is formed between the air chamber A and the air reservoir (formed by the bellows) by the tube 36. An air passageway between the air chamber A and the atmosphere is provided by the opening 37 in the plate 21 while the opening 38 forms an air passageway between the chamber B and the reservoir. Thus, it will be noted, each of the air chambers A, B, is provided with separate and

distinct air passageways communicating directly with the atmosphere and with the air reservoir. Associated with each of these air passageways are individual, one way flapper valves, specific valves being identified by the letters *a*, *b*, *c* and *d*. These valves are of identical construction and, as shown with respect to the valve *a*, may comprise a resilient pad 40 of leather, rubber or etc., cemented or otherwise affixed to a thin metallic strap 41 which, in turn, is secured in proper position with respect to the associated opening by a screw 42. The strap 41 is a weak spring and normally exerts a weak but definite pressure in the direction of the supporting surface so that the pad 40 is maintained in contact with the plate 21 except when the atmospheric pressure is somewhat lower than the air pressure within the chamber A.

One way, spring biased, flapper valves of the type shown in the drawing are known in the art, it being pointed out that the function of each valve is to permit the passage of air through the associated opening or passageway in but one direction. As a specific example, the valve *a* is normally closed by the slight mechanical bias exerted by the spring strap 41 but it is closed still tighter when the atmospheric pressure is greater than that within the chamber A. The valve *a* will move to the open position when the air pressure in chamber A is raised somewhat above atmospheric pressure by compression of the bellows 20. Similar desiderata holds for the flapper valves *b*, *c* and *d*, except that the individual valves are positioned to close and open the associated apertures or air passageways in accordance with a predetermined arrangement as will become more apparent hereinbelow.

The reed block 16 carrying the single vibratory reed 15 is secured across the opening 45 by the screws 46, or by means of beeswax as conventionally practiced, it being noted that the opening 45 forms the only air passageway in direct communication between the air chambers A and B. A lever 46 is pivotally secured to the plate 30 at the point P, said lever having a pad 47 of leather or other resilient material affixed to one end thereof. The lever 46 normally is biased in a counter-clockwise direction by the coiled spring 49 which may be retained in a fixed position relative to lever 46 by means of the screw 50. The pressure exerted by the spring against the lever 46 is sufficient to retain the pad 47 across the aperture or opening 45 to prevent passage of air therethrough. A rod 55, passing through the plate 21 serves as a means for rotating the bar 46 in a clockwise direction against the restraining action of the spring 49 to thereby permit the passage of air through the opening 45. The rod 55 may be finger-operated directly by the musician or may be connected to one of the keys of the accordion keyboard. In order to prevent leakage of air through the slight clearance opening between the rod and the associated hole in the plate 21, when the rod is not depressed, the rod may be provided with a head 56 carrying a leather or rubber washer 57. When the rod 55 is in the normal, non-depressed position the pad 47 closes the opening 45 and the pad 57 on the rod abuts against the under surface of the plate 21.

In the Figure 3 illustration the rod 55 is shown in the depressed or operative position, that is, the musician's finger is assumed to be pressing on the key to produce the tone corresponding to the vibration frequency of the particular reed 15.

Also, the bellows 20 are being expanded whereby the pressure of the air within the air reservoir is reduced below that of the atmosphere. Consequently, atmospheric air immediately will flow along the path indicated by the arrows, that is, through the tube 35, past the now open valve b, through the aperture in the reed block 16 and the opening 45, through the tube 36, past the now open valve d, into the air reservoir. Passage of the air through the reed block 16 sets the reed 15 into vibration thereby producing the musical tone. It will be noted that the valves a and c are tightly closed by reason of the normal bias of their spring plus the relatively increased air pressure against the face of the valve as indicated by the short, heavy arrows. The amplitude of the vibrations imparted to the reed 15 is determined by the velocity of the air passing through the aperture in the reed block 16 which, in turn, is governed by the pressure difference in the chambers A and B, the latter being a function of the speed with which the bellows are extended. Variations in the speed of extension of the bellows produce corresponding modulations in the degree of vacuum within the air reservoir which effects may be used in various ways to influence the amplitude of vibrations of the reed quite apart from the "on and off" control of the key-rod 55. The reed vibrations continue so long as the pressure in the air reservoir is sufficiently below that of the atmosphere and the rod 55 is depressed. When, however, the flow of air into the air reservoir results in an equalization of the atmospheric and reservoir pressures, air flow through the above explained passageways will cease.

If, now, the expanded bellows are compressed, the air in the reservoir is placed under a pressure above that of the atmosphere and the various valves will take the positions shown in Figure 4, it being noted that the rod 55 is still in the depressed position. Air from the reservoir escapes through the now open valve c, through the reed block 16 and the opening 45, and through the now open valve a. The valves b and d, which were open when the bellows were being expanded, are now tightly closed due to the small normal bias of their springs, plus the increased pressure exerted in the direction indicated by the short, heavy arrows. The air passing through the reed block 16 is in the same direction as in the above described condition when the bellows were being expanded. Consequently, the reed will vibrate to produce the tone.

It will now be apparent the single reed 15 will vibrate when the bellows are compressed or expanded and there is no need to provide a dual set of reeds as required in the conventional instrument. When the key-rod 55 is not physically depressed the pad 47 closes the opening 45 under the action of the relatively strong spring 49 thereby preventing the flow of air through the reed block 16 and under this condition the reed cannot vibrate in spite of the attempted expansion or compression of the bellows.

While the drawings and the description are restricted to a single reed and key-rod it will be understood a whole bank of similar air chambers and valves are arranged along one side of the accordion, each associated with a single reed having a pre-selected or adjusted vibration frequency, whereby the entire range of musical tones or notes is available to the musician. A similar air chamber arrangement is provided on the other side of the accordion as illustrated by the hous-

ing 60 and control button 61 in Figure 3. Since the action of both halves is the same only one is shown in detail. In actual practice one side of the accordion is arranged to produce a single tone upon depressing a single control key, as above described, while the other side is arranged to produce a cord upon operation of a single button. The multiple arrangement of the air chambers to cause vibration of a plurality of reeds is well-known in the art.

While I have illustrated my invention in a rather schematic sense it is believed the above detailed description affords a thorough understanding thereof.

The one way air valves may take a variety of specific designs. As shown in Figure 3, with specific reference to the flapper valve a, the resilient member 41 carrying the felt pad 40 is preferably made of spring material to impart a finite amount of mechanical bias to the valve as a whole. In such arrangement a pre-determined, minimum differential air pressure is required to open the associated port or air passageway. Further, the valves may be of the axially sliding type urged to a normally closed position by a helical spring, as is well-known in the art.

The specific construction of the air chambers A and B is also subject to a wide latitude of designs with respect to such considerations as size, shape, type of material, etc. In the above description I have indicated only a single reed with the pair of air chambers. It will be apparent the air chambers A and B may extend the full width of the accordion, that is, each chamber being common to the full complement of reeds, as the operation of each reed is controlled by an individual closure pad such as the pad 47, Figure 3.

Having now described my invention and the principle of operation, various modifications of practicable character will suggest themselves to those skilled in the art without constituting a departure from the spirit and scope of the invention as set forth in the following claims.

I claim:

1. An accordion comprising a bellows secured to spaced plates to form a variable-capacity air reservoir, one of said plates having an aperture normally closed by a one way air valve; a housing carried by the said plate and extending into the reservoir, said housing having an aperture communicating with the reservoir; a one way air valve normally closing the said housing aperture; a fixed partition dividing the interior of the housing into a first air chamber proximate to said plate and a second air chamber proximate to said reservoir, said partition having a reed aperture therein; a first hollow member forming an air passageway between the second chamber and the atmosphere; a one way air valve closing an end of said first hollow member; a second hollow member forming an air passageway between the first chamber and the reservoir; a one way air valve normally closing an end of the second hollow member; a vibratory reed carried by the said partition and operatively associated with the reed aperture; a pivotally mounted air valve normally closing the reed aperture; and a finger-operable member actuating the pivoted valve to open the reed aperture.

2. The invention as recited in claim 1, wherein the said first hollow member comprises a tube passing through alined holes in said face plate and partition, and the second hollow member

comprises a tube passing through aligned holes in the said partition and housing.

3. An accordion comprising a bellows secured to spaced plates to form a variable-capacity air reservoir, one of said plates having an aperture normally closed by a one way air valve and an unrestricted aperture; a housing carried by the said face plate and extending into the reservoir, said housing having a pair of apertures communicating with the reservoir; individual one way air valves associated with the housing apertures in opposed operative sense; a partition dividing the housing into a first air chamber proximate to the face plate and a second air chamber proximate to the reservoir, said partition having a reed aperture, an aperture normally closed by a one way air valve and an unrestricted aperture; a first tubular member passing through the said first air chamber and aligned with the unrestricted face plate aperture, and the normally closed partition aperture to form an air passageway between the second air chamber and the atmosphere; a second tubular member passing through the said second air chamber and

aligned with the unrestricted partition aperture and one of the housing apertures to form an air passageway between the first air chamber and the reservoir; a vibratory reed mounted on the partition and operatively associated with the reed aperture; an arm pivotally carried by the partition; a resilient pad carried by the arm and adapted to close the reed aperture; spring means normally biasing the arm to press the pad against the partition to close the reed aperture; and a finger operable member operable externally of the said face plate to overcome the bias of the spring means and space the pad from the partition.

BENJAMIN F. MIESSNER.
